UNITED STATES PATENT OFFICE.

SAMUEL W. JAMES, OF CHICAGO, ILLINOIS, ASSIGNOR TO BETTER TABLE SERVICE, INC., OF CHICAGO, ILLINOIS, A CORPORATION OF ILLINOIS.

DESIGN FOR A SERVICE PLATTER.

Original No. 73,744, dated November 1, 1927. Serial No. 23,222, filed August 27, 1927, for 3½ years.
Application for reissue filed December 17, 1927. Serial No. 24,521. Term of patent 14 years.

To all whom it may concern:

Be it known that I, SAMUEL W. JAMES, a citizen of the United States, residing at Chicago, in the county of Cook and State of Illinois, have invented a new, original, and ornamental Design for a Service Platter, of which the following is a specification, reference being had to the accompanying drawing, forming a part thereof.

The figure is a plan view of a service platter, embodying my design.

I claim:

The ornamental design for a service platter, as shown.

In testimony whereof I have signed my name to this specification.

SAMUEL W. JAMES.
